GAME COUNTER OR SIMILAR ARTICLE

Filed March 15, 1949

FIG. 1.

FIG. 2

STANLEY FREDERICK FUCHS, INVENTOR.

BY Stanley Fuchs
ATTORNEY

UNITED STATES PATENT OFFICE

162,020

GAME COUNTER OR SIMILAR ARTICLE

Stanley Frederick Fuchs, Janesville, Wis.

Application March 15, 1949, Serial No. 1,403

Term of patent 14 years

(Cl. D34—13)

To all whom it may concern:

Be it known that I, Stanley Frederick Fuchs, a citizen of the United States, residing at Janesville, county of Rock, State of Wisconsin, have invented a new, original, and ornamental Design for a Game Counter or Similar Article, of which the following is a specification, reference being had to the accompanying drawing, forming a part hereof.

Fig. 1 is a top perspective view of the game counter or similar article, showing my new design; and

Fig. 2 is a bottom perspective view thereof.

The game counter or similar article is of conventional thickness.

I claim:

The ornamental design for a game counter or similar article, substantially as shown and described.

STANLEY FREDERICK FUCHS.
